(57) **CLAIM**

The ornamental design for a shed hair removal device, as shown and described.

DESCRIPTION

FIG. 1 is a top front perspective view of a shed hair removal device, showing my new design;

FIG. 2 is a top rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a top front exploded perspective view thereof. The broken lines shown in the drawings depict portions of the article that form no part of the claimed design.
